(57) **CLAIM**

The ornamental design for an insect bait station, as shown and described.

DESCRIPTION

FIG. 1 is an upper perspective view of the insect bait station in an open position.

FIG. 2 is a bottom perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof.

FIG. 8 is a rear view thereof.

FIG. 9 is an upper perspective view of the insect bait station in a closed position.

FIG. 10 is a bottom perspective view thereof.

FIG. 11 is a top view thereof.

FIG. 12 is a bottom view thereof.

FIG. 13 is a right side view thereof.

FIG. 14 is a left side view thereof.

FIG. 15 is a front view thereof; and,

FIG. 16 is a rear view thereof.

The figures are schematic and not necessarily drawn to scale.
